UNITED STATES PATENT OFFICE.

AARON GRODSKY, OF CINCINNATI, OHIO, ASSIGNOR TO AMERICAN TOBACCO MACHINERY CORPORATION, OF NEW YORK, N. Y., A CORPORATION OF DELAWARE.

TOBACCO-STEMMING MACHINE.

Application filed December 12, 1921. Serial No. 521,820.

To all whom it may concern:

Be it known that I, AARON GRODSKY, a citizen of the United States, residing at the city of Cincinnati, in the county of Hamilton and State of Ohio, have invented certain new and useful Improvements in Tobacco-Stemming Machines, of which the following is a specification.

The object of my invention is to produce a simple and highly efficient machine for stemming tobacco leaves, each leaf being acted upon similarly and the stem cut therefrom in a precise and positive manner, and during the operation of the machine, feeding, brushing, cleaning and smoothing out both sides of the tobacco-leaf; the machine finally carrying the finished leaves by means of a belt system over and onto a revolving drum upon which they are deposited and held one on top of the other so that they lie practically in juxtaposition and means for removing the deposited leaves in bulk from the said drum; forming an apparatus possessing great utility.

One of the salient features of my invention consists in providing a smooth drum upon which the tobacco leaves are wound, one above the other, lying approximately in juxtaposition, and building up said pile of tobacco leaves until they have accumulated to a material thickness; and providing means for exposing the drum so that said bulk bunch of leaves may be readily removed.

Another feature consists in automatically stopping the machine when the cylinder has completed one revolution and had the tobacco leaf wound upon it; the next leaf can then be inserted; the operator at the same time stepping upon a treadle for each revolution of the cylinder, as each leaf is placed into the machine; only one treadle being used in the operation of the machine.

Another feature consists in cutting the stem out of the leaf before it is wound upon the drum.

The machine is made simple and can be placed into a small space, can be readily repaired and easily manipulated.

Its other features and advantages will readily become apparent from a perusal of the following specification and claim.

I may state that my present invention is an improvement on my Letters Patent 1,225, 55 240, of May 8th, 1917.

In the accompanying drawings forming part of this specification:

Fig. 1, is a plan view of the machine;

Fig. 2, is a side elevation of the machine;

Fig. 3, is a diagrammatic section on line 3-3 of Fig. 1,

Fig. 4, is a partial section on line 4-4 of Fig. 2,

Fig. 5, is a side elevation of the cam mechanism,

Fig. 6, is a plan view of said cam mechanism, and

Figs. 7, 8, 9, 10 and 11 are views showing various positions of said cam mechanism.

The frame of the machine is marked 1, which may be of any construction; mounted in the frame, I suitably journal a shaft 2 in which I mount the clutch pulley 3, which drives said shaft. On shaft 2 I also mount pinion gear 4 meshing with gear 5, which carries the pinion 6 meshing with the gear 7 on the shaft 8, (see particularly Fig. 1); the shaft 8 carries the roller 42 and male cutting knife 9 operating in conjunction with the female knives 10, (see Figs. 1, 2, and 3) mounted on shaft 12.

On shaft 8, is a gear 13 meshing with gear 14 on shaft 12, carrying roller 70. This gear 14 also meshes with the gear 15, on a shaft 16, which carries a roller 17, (see Figs. 2 and 4); and a stem stripper 18, which operates to take the stem from between the blades of the female knife; gear 13 also meshes with gear 19 on shaft 20 which carries the feed roll 21.

On shaft 8, I also mount mitre gears 22 and 22, meshing with gears 23 on short shafts carrying the bevel pinion gears 24 meshing with the bevel gear 25 on the shaft 26, which carries gear 27, meshing with gear 28 on shaft 29. On the shafts 26 and 29 are mounted the brushes 30, one upper and one lower brush, at each side of the machine which are set diagonally as shown.

On a shaft 31 journaled in frame 1, at each side, I mount a drum 32, cylindrical in shape. On said shaft 31, I also mount the cam 33 and the gear 34, which is driven through the intermediate gears 35 and 36, meshing with the gear 13.

For the purpose of holding the tobacco leaves in place on the drum 32 I provide the belts 37, 37^a and 37^b. All these belts encircle drum as shown in Fig. 3; and are all held in operative position with the drum

by reason of the spring pressed rollers 38, one for each belt, each of which is on a bell crank 39, operated by a spring 40.

For purposes of feeding, the two middle belts 37 of the series of belts, extend forward to a roller 41 in front of the brushes 30; the other belts passing around the rollers 42 on shaft 8.

I will now describe the travel of the 10 belts:—The central belts 37 travel from where they pass over the roller 41, toward the right and under the feed rollers 42^a and 21, between the rollers 42 and 70, thence under the stripper roller 17, around the 15 drum 32, under the roller 47, over guide rollers 49 and 50, around roller 38, and thence under roller 51 back to the roller 41. The two belts 37^b pass over roller 42, drum 32 and rollers 45, which drive the 20 cylindrical brush 46. From rollers 45, said belts 37^b pass over rollers 49, 50, 38 and 53 back to roller 42. Belts 37^a pass over the roller 42, around the drum 32, and then over the rollers 47 mounted on shaft 48, thence 25 over rollers 49, 50, 38 and 53 back to roller 42. The brush 46 functions to clean the belts 37 and 37^a after they have deposited the leaves on the drum 32. The belts 37 in passing under the roller 51 move beneath an inverted V-shaped shield 52, which 30 prevents the falling stems from landing on the belts 37.

On the frame 1, is a shaft 44 carrying near its center, the links or arms 43 which 35 carry the roller 42^a, (see Figs. 1 and 3). Said roller 42^a has an annular groove for the passage of the leaf stem and this roller rests on the belts 37 to facilitate feeding of the tobacco leaves.

40 In the operation of this machine, the tobacco leaves are placed upon the belts 37 and fed under the rollers 42^a and 21. Each leaf passes between the brushes 30 which remove dust and smooth the leaf out. 45 After passing between the brushes, the leaf passes between the rollers 42 and 70 and the cutters 9 and 10 cut the stem from the leaf. Then the leaf passes under the stripping roll 17 and then follows the belts and 50 is wound on the drum 32. To facilitate removing the tobacco leaves 100, it is desirable that they be placed in superposed relation upon the drum 32 and do not overlap at their ends, and to provide for this the 55 drum is made of sufficient diameter to receive the largest tobacco leaves. To facilitate winding of the leaves on the drum I have provided means to control the operation of the drum 32 so that the latter will stop 60 at the same point automatically after each complete revolution.

When a tobacco leaf is fed onto the belts 37 and under feed roll 42^a, the foot pedal 61 is depressed by the operator and this 65 causes the link 62 to rock the bell-crank

lever 63 in a clockwise direction (see Figs. 6 to 11, inclusive). This stretches spring 62^a which normally tends to pull link 62 upwardly. As the bell-crank lever 63 rocks in a clockwise direction, and moves from position shown in Fig. 6 to that shown in Figs. 5 and 8, its upper end 69 will press against the finger 69^a of a latch plate 65, which is pivoted at 65^a on a double ended lever 64 and is yieldingly held in normal position by a spring 65^b. The continued pressure of the end 69 on said finger 69^a causes the latch plate 65 to swing in an anti-clockwise direction until one of its edges strikes the depending arm of a bell-crank lever 66—67, as shown in Fig. 8. At 70 this time the roller 72 on the arm 66 of said bell-crank is abutting against the cam 33 (see Fig. 5), so that the bell-crank cannot move in a counter-clockwise direction. Consequently the end 69 will then cause the double-ended lever 64 to swing in a counter-clockwise direction about its pivot 64^a, and throw the movable member 64^b of the clutch into clutching position (see Fig. 11). 75 While the lever 64 is moving it will stretch its return spring 64^c and finally cause the shoulder 68 of the latch plate to catch on the arm 67, as shown in Figs. 10 and 11. When the parts are in this position, the 80 cam 33 will be revolved in a counter-clockwise direction, and the operator cannot disturb the clutch, for the movement of the pedal will merely cause the end 69 to move along the slot 64^d of the lever 64. As the 85 cam 33 nears the end of a complete revolution (see Fig. 7), its portion 71 will first gently depress the arm 66 and the bell-crank 66—67 will gradually release the nose 90 95 100 105 110 115 I wish to be understood as claiming that such modification or changes will fall within a scope of this specification and claim.

What I claim as new and my invention 5 and desire to secure by Letters Patent is;—

In a tobacco stemming machine having a front lower roller, rear upper and lower rollers having male and female knives at their central portions for cutting a stem 10 from a leaf passing between the rear rollers, a front upper roller arranged between the rear rollers and front lower roller and having an annular groove aligned with said cutters to receive the stem of a leaf fed to 15 the cutters, pivotally mounted arms carrying said front upper roller and adapted to permit the front upper roller to be raised while inserting a leaf beneath the same, pairs of upper and lower brushes diverging 20 from said front rollers and adapted to smooth and clean a leaf as it passes between

the front rollers, a stem stripping roller arranged rearwardly of the rear rollers and having a circular stripper wheel extending into the female cutter, a booking drum arranged rearwardly of the stripping roller, 25 guide rollers, the combination of a central pair of belts passing between the front rollers and rear rollers, beneath the stripper roller, around the drum and then over the guide 30 rollers back to the lower front roller, two pairs of side belts out of contact with the front rollers and passing between the rear rollers, beneath the stripper rollers, around the drum and then over the guide rollers 35 back to the lower rear roller, and positive means for driving the brushes, front upper roller, rear rollers, stripper roller and drum.

In testimony whereof, I affix my signature at Cincinnati, Ohio, this 9th day of 40 December, 1921.

AARON GRODSKY.
